UNITED STATES PATENT OFFICE.

WILLIAM O. KLEINE, OF CINCINNATI, OHIO.

CLAMP HOLDER.

Application filed December 1, 1922. Serial No. 604,244.

My invention relates to devices for clamping and holding in place, hollow cylindrical or globular objects in which it is desirable to clamp and hold the article under spring tension, and it more particularly relates to devices for holding glass or metallic shades, globes, or other parts in connection with lighting fixtures of various kinds.

While I have illustrated my invention as 10 designed for use as a most effective and quickly operated holder for securing light globes as employed both in inside and outside lighting, it may also be effectively applied for automobile headlights in holding 15 the lens in position, and in many other situations which will readily occur to the skilled mechanic, should occasion arise.

The invention consists broadly of a clamping device involving two disk plates secured 20 together and relatively movable rotatively to a limited degree and provided, mounted to oscillate on a fixed center, with reference to each other, with resilient clamp plates of comparatively thin metal mounted upon 25 studs secured to one of the plates to engage slots in the other plate and actuated by the movement of the latter plate to oscillate the clamp plates into and out of locking position.

30 In the drawings,

Figure 1 is a perspective view of a globe holder for a pendant electric light fixture with my improved clamping device.

Figure 2 is a central vertical section of 35 the device applied to both the top and bottom inside flanges of a light globe, such as is used for outdoor lighting.

Figure 3 is a detail section showing the clamping device arranged for holding two 40 sections of a light globe, both sections constructed of glass.

Figure 4 is a vertical section of a portion of a fixture, showing a modification of the clamp plate holder.

45 As illustrated in Figure 1, 1 is the metal casing of a pendant light fixture used for interior or exterior lighting. Across the lower open end of the casing, within the depending rim 3, is secured a disk plate 2 by bolts 4, shown in Figure 2. Depending from this plate and secured thereto are a plurality of studs 5 which project through segmental slots 6, 6, in a second plate 7 mounted for 50 limited rotative movement with reference to the fixed plate 2.

The studs 5 are preferably three in num-

ber distributed 120 degrees apart, and they carry the clamping devices marked 8 as a whole. Each clamping device 8 comprises a member 12 mounted to turn on its stud. 60 Where the two plates 2 and 7 are flat and located close to each other, in order to bring the clamping piece in proper position to engage the globe and to exert the pressure practically at right angles to the glass to 65 be held, I preferably construct this member 12 of U-shape. The inner arm of the U-shaped member has an arm or hook 9 which engages in a slot 10 in the plate, and these slots 10 are radially disposed, while 70 the slots 6 are on the arc of a circle.

The outer arm of the U-shaped member is formed with a flat surface 13, upon which is riveted a thin, properly proportioned, spring metal plate 19 curved 75 slightly outwardly.

When the plates 2 and 7 are not located close together, as shown in Figure 4, the member 12, instead of being U-shaped, is simply a flat plate, and it will be understood that the shape of the member 12 is not of importance, its shape being dependent upon the position in which it may be necessary to locate the spring metal plate 19 in order that it may exert its pressure 85 approximately in the direction of the axis of the member to be held.

In order to turn the plate 7 to cause the hooks 9 to actuate the clamp member and clamp plate, I provide a handle 14, which, 90 in the case of the pendant fixture illustrated in Figure 1, projects radially through a slot 16 in the rim 3 of the metal piece 1. To co-operate with this handle 14, I provide also, for this construction, a pair 95 of fixed handles 17, 18, secured to the outside of rim 3, so that, to turn the disk 7 in either direction, the operator, with one hand, may hold the fixture by handles 17, 18, and pull the handle 14 towards either 100 of the fixed handles 17, 18, while, at the same time, he can hold the globe with the other hand.

It will be evident from the construction described that actuation of the plate 7 in 105 this way will turn the clamp members on the studs and rock the clamp plate 19 out or in to grasp or release the glass shade or globe 20 on the inside.

These holders may be employed both for 110 the top and the bottom of the globe. As illustrated in Figure 2, I show the clamp

holder for mounting the globe 20 on top of a fixed standard or support, the upper end of the standard being indicated at 22. In this position, the fixed plate is shown at 2^a and the movable plate at 7^a. The movable plate is provided with the up-turned flange 23. The globe 20 rests on the movable plate and the clamp plates 19 engage over the inner ridge of the globe and hold it resiliently. For conveniently operating the clamp in this position, the handle 14, secured to the rim 23 of the movable plate, may be used alone, as there is no danger of the globe dropping out when the clamp plates are released. For using the clamp holder to secure a canopy 1 to the top of the globe 20, there is no change in the mechanism. The clamp members, in this event, are mounted on the under side of the plate 7, and the clamp plates 19 engage under the contracted edge or inner ridge of the upper end of the globe. In this position, the handles 14, 15 and 17 for turning the clamp member project downwardly, so that the metal canopy is first secured to the top of the globe and the operator inserts his hand within the globe to manipulate the clamps, by means of the handles 14, 16 and 17.

In the event that it is desired to clamp together two members of glass, for example, if the top or canopy of the globe in a street lamp is constructed of glass, I use the modification illustrated in Figure 3, in which the top piece 1^a is provided with an inwardly projecting ridge 24, which is engaged by the clamp plates 19^a as shown in Figure 3. In this modification, the fixed plate 2^b is provided with clamp studs 5^a, which extend both above and below the plate, and the U-shaped piece 12^a also extends above and below the plate through a slot in the plate to allow it to turn. The clamp plates 19^a are duplicated for this U-shaped piece, the upper plate curved upwardly and the lower one downwardly. In this way, the two glass members are held resiliently against the fixed plate 2^b and are separated from each other, so that there is no danger of breakage through jars and vibration. Moreover, as the glass members are held resiliently against the outer edge of the plate 2^b, an effectual seal against the entrance of moisture or rain is provided, and, if desired, ventilation may be provided by perforating the plate 2^b near its outer edge.

It will be noted that the clamp plates are applied to the globe or other part to be clamped upon the inside of the globe, and

that, with my construction, the clamp plates can always be located so as to apply the pressure in the direction of the axis of the globe instead of outwardly or inwardly, and thus it is practically impossible to break the globe when the clamps are applied.

It will also be noted that, inasmuch as the clamp plates are inside, there is no liability of water collecting between the clamp and glass to become frozen in cold weather when exposed outside, and that there is also no liability of water freezing the globe to other metal parts. Moreover, when two glass globes or other parts of glass are to be secured together the glass members are not allowed to come in contact with each other, and liability of breakage under vibrations or jars is thus obviated.

Having thus described my invention, what I claim as new and desire to secure by Letters Patent, is:—

1. The combination with a support for a lamp globe and a circular plate associated therewith, of a rotatively movable plate mounted parallel to said circular plate and provided with a radial aperture and a concentrically curved aperture, a stud carried by said circular plate and projecting into said concentrically curved aperture in said movable plate, and a member mounted upon said stud extending through said curved aperture in said circular and said movable plates, and provided with a projection to engage said radial aperture and with globe clamping portions on opposite sides of said plates that are movable into and out of clamping position as the rotatively movable plate is moved in the one or the other direction.

2. The combination with a support for a lamp and a circular plate associated therewith, of a rotatively movable plate mounted parallel to said circular plate, a stud carried by said circular plate and projecting through said movable plate, a member mounted upon said stud and provided with a projecting portion for engaging said movable plate and with globe clamping portions on opposite sides of said plates, said plates being provided with openings for said stud and the projecting portion on the said member mounted thereon whereby said globe clamping portion is moved into and out of clamping position as the supporting plate is rotatively moved into the one or the other direction.

WILLIAM O. KLEINE.
